Primary Examiner — T Chase Nelson*Assistant Examiner* — Jonathan J. Han(74) *Attorney, Agent, or Firm* — Harness, Dickey & Pierce, P.L.C.(57) **CLAIM**

The ornamental design for a high profile archery bow holder for a tree stand, as shown and described.

DESCRIPTION

FIG. 1 is a perspective view of a high profile archery bow holder for a tree stand embodying my new design;

FIG. 2 is another perspective view thereof;

FIG. 3 is a right side view thereof, the left side being a mirror image of the right side view;

FIG. 4 is a top view thereof;

FIG. 5 is a front view thereof;

FIG. 6 is a rear view thereof; and,

FIG. 7 is a bottom view thereof.

The broken lines are used to illustrate unclaimed environmental structure and form no part of the claimed design.

1 Claim, 4 Drawing Sheets(56)
